T. G. JOHNSON

MOP HEAD

Filed Feb. 24, 1925

Fig. 1.

Fig. 2.

INVENTOR
Theodore G. Johnson.
BY *Arthur L. Brown*,
ATTORNEY

UNITED STATES PATENT OFFICE.

THEODORE G. JOHNSON, OF KANSAS CITY, MISSOURI.

MOP HEAD.

Application filed February 24, 1925. Serial No. 11,029.

This invention relates to mop heads and the primary object is to provide an improved form of hinge for connecting the mop handle to the head and providing a reinforcing or expansion member for the sides of the mop head frame so that liability of the side bars of the mop head frame being bent inwardly when the operator taps the head against an object to dislodge the dust from the mop fabric will be eliminated.

The novel construction of my invention will be apparent by reference to the following description in connection with the accompanying drawings, in which

15 Fig. 1 is a perspective view of a mop head constructed in accordance with my invention, and

Fig. 2 is a fragmentary plan view of the same.

20 The mop head is shown as comprising a closed loop formed by bending a strand 1 of wire intermediate its ends to provide an eye 2, bending the strand again to provide the toe 3 of the loop, bending the strand 25 to form another eye 4 diametrically opposite the eye portion 2, and bending the other end of the strand to provide a wider portion or heel 5 of the frame, the end terminating in an eye portion 6 in line with the eye portions 2 and 4. Through these eyes is introduced a bolt or pintle 7 which passes through the eyes 8 and 9 on the bail 10 fastened to the handle 11 and secured by the ring 12 so that when the cross bar 13 is in the opening 30 14 the side bars of the bail will be held in rigid engagement with the handle 11. Between the eyes 8 and 9 is a coil expansion spring 15 which surrounds the bolt or pintle 7 and which exerts enough pressure against the eyes 8 and 9 to hold the eyes 8 and 9 in frictional contact with the eyes 2 and 6 so that the bail may hinge on the pintle or bolt 7 but be in frictional engagement with the

main frame of the head, and a very important feature of my invention is that the 45 spring is strong enough to resist bending of either of the side bars 16 and 17 of the frame in the event that the operator knocks the edge of the side frame, that is one of the bars, against a window sill or other object to 50 free the swatch from accumulations.

It will be apparent that liability of the frame becoming distorted by pressure or knocks against the side bars will be eliminated because the expandible element illustrated as the spring 15 will resist tendency of the bars 16 and 17 to move one toward the other.

What I claim and desire to secure by Letters-Patent is:—

1. In combination, a mop head frame formed of an elongated wire loop bent to form aligning eyes intermediate its ends, a bolt passing through the eyes, a handle connection having eyes about the bolt, and an expandible spring around the bolt, the opposite ends of which bear against the eyes on the handle connection.

2. In combination, a mop head frame, comprising a strand of wire bent intermediate its ends to provide aligning eyes, a bolt passing through the eyes, a handle securing means carried by the bolt having said bars engaging said bolt, and means on the bolt between said side bars for preventing inward movement of the side bars.

3. In combination, a mop head frame, aligning eyes carried by the frame, a bolt passing through the eyes, a handle bail carried by the bolt, and a coil spring on the bolt between the ends of the bail, the ends of the spring contacting with the end of the bail to force the same against said eyes.

In testimony whereof I affix my signature.

THEODORE G. JOHNSON.
